UNITED STATES PATENT OFFICE.

FRANK J. MIRGON, OF SAN FRANCISCO, CALIFORNIA.

RAZOR-HONE HOLDER.

Application filed November 2, 1922. Serial No. 598,610.

To all whom it may concern:

Be it known that I, FRANK J. MIRGON, a citizen of the United States, residing at San Francisco, in the county of San Francisco, State of California, have invented a new and useful Razor-Hone Holder, of which the following is a specification, in such full and clear terms as will enable those skilled in the art to construct and use 10 the same.

This invention relates to a razor hone holder, and its object is to produce a holder which is capable of being turned to secure the hone in any desired convenient angle 15 for use by the person sharpening the blade.

It will be understood by those skilled in the art that persons honing a razor are very particular about the manner of holding a hone, and the particular slope the hone 20 may have when the blade is being sharpened.

With the present invention the hone holder can be tipped with respect to the base in any direction, and with the shift of the 25 base particularly gives the operator any position he may fancy.

A further object of the invention is to produce a hone holder which will be very simple to construct and compact in form.

30 Other objects of the invention will appear as the description proceeds.

An embodiment of the invention is shown in the accompanying drawings in which the same reference numeral is applied to the 35 same portion throughout, but I am aware that there may be modifications thereof.

Fig. 1 is a side elevation of the hone holder with the hone in substantially horizontal position.

40 Fig. 2 is a view of the hone holder looking at right angles to Fig. 1.

Fig. 3 is a plan view of the hone holder with the hone removed therefrom, and

45 Fig. 4 is a side elevation of the base with the holder removed therefrom.

The numeral 1 indicates a solid metal base and 2 a felt or cloth bottom which is suitably secured to the base to prevent the metal base from marring the finish of a 50 table upon which the hone holder may be placed.

At its center the hone holder has a stand 3, the upper end of which is spherical.

The hone holder proper consists of a flat plate 5, which has slots cut therethrough 55 to pass depending ears 6 and 7 of the hone holding plates 8 and 9. These plates rest loosely in grooves of a soft rubber pad 10 and there are four of the plates, two at each end of the rubber pad. 60

Two right and left-handed threaded screws 10' and 11 pass through the depending ears 6 and 7 of the plates 8 and 9, and said screws also pass through depending slotted ears 12 and 13 of the plate 5. When 65 the hone 15 is placed on the top of the rubber pad, plates 8 and 9 are clamped against the hone; the only thing that holds the hone in place is the pressure the clamps 8 and 9 exert upon it and exert upon the 70 rubber pad, whereby a considerable yielding movement of the hone is permitted.

On the under-side of the plate 5 there are two quarter-spherical plates 16 and 17. 75 These plates each have ears 18 and 19 through which bolts 20, 21 pass, wing-nuts 22 being used to tighten the plates against the spherical plates on the top of the standard.

In use the hone may be turned down or pulled to one side in any convenient direction by simply loosening the screw 20, 21 and turning it to the desired angle, whereupon the screws 20, 21 are again tightened 80 and the hone is ready for use in the desired position. It will be seen that while the clamps hold the hone securely that the resiliency of the rubber pad 10 allows the hone a certain amount of movement which the expert finds necessary for the proper sharpening of a razor. 85

What I claim is as follows, but various modifications may be made in the construction shown in the drawings and above particularly described form, within the purview of my invention: 95

1. A razor hone holder, comprising a flat base, a standard having a spherical head carried by the base, resiliently supported hone-holding clamps, a pair of partly spherical members having means to tighten them on said head in any given angle of adjustment and a plate for loosely connecting the latter members to the clamps. 100

2. A razor hone holder, comprising a 105 base, a standard having a spherical head

carried thereby, two pairs of hone holding hone in any desired angle of adjustment clamps, a grooved rubber pad to act as a support for said clamps, a pair of partly spherical clamps adapted to embrace the spherical head on the standard and means to tighten said partly spherical members against the spherical head to secure the

In testimony whereof I have hereunto set my hand this 25th day of October, A. D. 1922.

FRANK J. MIRGON.
